UNITED STATES PATENT OFFICE

2,645,354

HOLDER

Clifton R. Bradley, Bedford, Ohio

Application April 27, 1951, Serial No. 223,403

1 Claim. (Cl. 211—69)

1

This invention relates to new and useful improvements in holding devices and the primary object of the present invention is to provide a device for holding pens, pencils, tools, nut-picks and crackers, kitchen utensils, dressmaker's, artist's, surgical and/or other such instruments and articles, conveniently within reach and sight.

Another important object of the present invention is to provide a container having a base removably positioned therein and a plurality of upright resilient and flexible finger-like members attached to the base for holding articles in an upright position.

A further object of the present invention is to provide a holder of the aforementioned character composed of a plurality of vertical and parallel members formed from corded wire having cotton or other suitable material such as covering, so that articles placed therein will be free from wear, soil, scratches or the like.

A still further object of the present invention is to provide an article holder that is extremely neat and attractive in appearance, simple and practical in construction, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the present invention in use;

Figure 2 is a vertical sectional view taken substantially on the plane of section line 2—2 of Figure 1;

Figure 3 is an elevational view of one of the vertical finger members that is used in conjunction with the present invention and showing the manner in which the same is bent to the desired shape; and

Figure 4 is an enlarged fragmentary view of Figure 2 illustrating the manner in which the finger members are anchored to their supporting base.

Referring now to the drawings in detail, wherein for the purpose of illustration, there is disclosed a preferred embodiment of the present invention, the numeral 10 represents a cylindrical container, through the open end of which is received a supporting base or plate 12 that rests against the bottom wall 14 of the container.

A plurality of vertical finger members 14 are anchored to the base 12 and the members 14 fill

2

the container 10. Each of the members 14 includes at least one lower hump or bend 16 that is anchored to the upper face of the base 12 by suitable cement 18. The corded members 14 are of wire 20 covered with cotton or other suited material 22. The exposed bottom ends of the finger members 14 are secured by cement to base 12.

A supporting panel 26 is adapted to removably support one or more of the containers 10. The panel 26 is formed with a suitable number of recesses 28 in its upper face that receive the lower ends of the containers 10, as shown best in Figure 1 of the drawings.

In practical use of the present invention, the base 12 and the removable container 10 hold and contain the resilient, flexible finger members 14 and the fingers are all firmly cemented to the base 12.

Any suitable article or articles are inserted 20 downwardly into and between the vertical fingers of the members 14 and the article or articles will be retained upright, in sight and easy to reach and withdraw, the resilient fingers being always ready to receive articles placed at any point 25 amongst them.

The container 10 shown in the drawings and designed to make clear the purpose and intent of the invention, is cylindrical. However, the container may be of such other shape with the recesses 28 shaped to receive the lower end of 30 the container.

It is anticipated that pipe cleaners or like fabrication, may be employed as the means forming the finger members 14 within the container 35 10 as best shown in Figure 2. The fingers of member 14 are formed by bending at desired even and equal lengths to form the fingers that are closely set together within the removable container 10.

In view of the foregoing description taken in conjunction with the accompanying drawings, it is believed that a clear understanding of the device will be quite apparent to those skilled in this art. A more detailed description is accordingly 40 deemed unnecessary.

It is to be understood, however, that even though there is herein shown and described a preferred embodiment of the invention, the same 45 is susceptible to certain changes fully comprehended by the spirit of the invention as herein described and the scope of the appended claim.

Having described the invention, what is claimed as new is:

An article holder comprising a base, and a plu-

rality of undulated resilient members each having a soft covering and a wire core, said members including upper and lower humps and vertical portions joining said upper and lower humps, adjacent vertical portions of each member being in contact with each other, said lower humps being adhesively secured to said base.
